UNITED STATES PATENT OFFICE.

JAMES ALEXANDER HORTON, OF PROVIDENCE, RHODE ISLAND, ASSIGNOR TO THE
BRITISH STEEL & WIRE COMPANY, LIMITED, OF MANCHESTER, ENGLAND.

MACHINE FOR TAPERING WIRE.

1,013,016.

Specification of Letters Patent. Patented Dec. 26, 1911.

Application filed June 23, 1911. Serial No. 634,980.

To all whom it may concern:

Be it known that I, JAMES ALEXANDER HORTON, a citizen of the United States of America, residing at 10 Weybosset street, Providence, Rhode Island, United States of America, have invented certain new and useful Improvements in Machines for Tapering Wire, of which the following is a specification.

10 This invention relates to a machine for tapering wire in accordance with the method described in my prior application for Letters Patent of the United States Serial No. 546,227 filed on the 26th February 1910, and 15 has for its chief object to construct a simple and efficient machine for carrying out such method.

Important features of the invention comprise a hand operated device for increasing 20 or diminishing the amount of taper that is imparted to the wire during the tapering operation.

In order that the said invention may be clearly understood and readily carried into 25 effect the same is described with reference to the accompanying drawings, in which:—

Figure 1 is a vertical section taken on line 2—2 of Fig. 2 of a taper wire drawing machine constructed in accordance with this 30 invention. Fig. 2 is a plan of the machine. Fig. 3 is a transverse section taken on line 3—3 of Fig. 2. Fig. 4 is a detached section of the wire tapering head drawn to a larger 35 scale. Fig. 5 is a plan of the head and Fig. 6 is a front elevation of the head showing the measuring device. Fig. 7 is a detached view of the measuring device drawn to a larger scale.

A indicates the wire and B the die; the 40 latter is constructed from a solid piece of metal having an external surface conical in form to fit in a correspondingly shaped hole in a die socket b that is carried by the frame C of the wire tapering head.

45 D indicates a two-armed lever pivoted at d in the frame C. The short arm d' of this lever is situated in line with the die B and interposed between the latter and the arm d' is a die prop b' and a removable thrust 50 block b² which permits of the insertion and removal of the die and die prop from the

die socket. The long arm d² of the lever D bears against the end of a screwed spindle E that is slidably mounted in bearings c in the frame C and is provided with means whereby it is operated by movement of the winding drum H to force the solid die into the conical die socket at a predetermined speed in relation to the said movement of the winding drum whereby the die orifice 60 is gradually contracted and imparts the desired amount of taper to the wire. In addition to this arrangement the machine is also provided with the aforesaid hand operated device whereby the amount of taper can be 65 increased or diminished while the drawing operation is taking place. In the example shown for effecting these purposes two worm wheels E' and F are mounted upon the spindle E between transverse portions of 70 the frame C, the worm wheel E' being threaded internally to engage with the threaded portion of the spindle and the worm wheel F having a key f which engages with a keyway e extending along the spindle E. By this arrangement rotation of either of the worm wheels produces relative movement between the threaded portions of the spindle and of the worm wheel E' with the result that an endwise movement is imparted to the spindle. The worm wheel E' 75 is driven by gearing from the main driving shaft G on which is a bevel wheel g gearing with a bevel pinion g' on a shaft g² that is driven from any suitable source of power 80 through the counter-shaft g³ and gear wheels g⁴ and g⁵. The shaft G imparts motion to the wire drawing drum H through the pinion h and spur wheel h'. In the example shown the gearing for rotating the 85 worm wheel E' comprises a bevel wheel g^x that is rigidly fixed upon the shaft G; this wheel gears with a bevel wheel e' rigidly fixed upon a shaft e² on which is also fixed another bevel wheel e³. The latter gears 90 with a bevel wheel e⁴ carried by an upright shaft e⁵ on which is also fixed another bevel wheel e⁶. The latter gears with a bevel wheel e⁷ that is keyed or otherwise secured upon the boss of a pinion e⁸ rotatably 100 mounted upon a stud e⁹ that is carried by a portion of the frame C and constitutes one

wheel of a train of wheels e^{10} , e^{11} , e^{12} , e^{13} , e^{14} , the last mentioned wheel being rigidly connected with a worm e^{15} that gears with the worm wheel E' .

5 In order to increase or diminish the amount of taper imparted to the wire during the drawing operation the worm wheel F is arranged to be operated by hand from a worm f' keyed upon a shaft f^2 on which 10 is also fixed a hand wheel f^3 .

For the purpose of ascertaining whether the desired taper is being imparted to the wire during the working of the machine a measuring device is attached to the frame 15 C of the tapering head in front of the die opening. In the example shown the measuring device comprises a bracket J that is bolted at j to the frame C and is formed with a curved arm j' and with an arm j^2 that extends transversely below the wire A . Pivoted to the bracket J in proximity to the wire A is a lever j^3 which extends transversely above the wire and is connected at its free end by a hook joint with a finger j^4 20 extending from a lever j^5 in proximity to the pivot j^6 thereof that is situated at the end of the arm j^2 . The free end of the lever j^5 terminates in proximity to the arm j' and serves as a pointer or indicator for graduations j^7 that are formed upon the curved arm j' . Interposed between the arm j^2 and the lever j^3 are two blocks j^8 , j^9 , of which the upper block j^8 is connected to a spring j^{10} that is fixed in the lever j^5 , the lower block j^9 being supported by the arm j^2 . These blocks bear against opposite sides of the wire and any slight movement of such blocks due to variations in the diameter of the wire during the tapering operation results in a multiplied movement being imparted to the free end of the lever which 40 travels over the graduations j^7 on the arm j' and thereby indicates the progress of the tapering operation. j^{11} represents an adjusting screw for bringing the free end of the lever into alinement with any of the 45 graduations on the arm j' , the pressure of the spring j^{10} upon the end of the screw j^{11} retaining the latter in any adjusted position 50 against vibration that may be set up by the working of the machine or by the tapering operation.

In the operation of the mechanism, the rotation of the worm wheel E' , through the 55 gearing described, causes the gradual elevation of the spindle E , because said spindle cannot revolve due to the worm F and the key f of the latter, the worm f' preventing the worm wheel F from revolving. The 60 resulting gradual elevation of the long arm of the lever D causes the short arm of said lever to forcibly drive the die B into the socket b , thus gradually compressing the

material of which the die is composed so that the wire passing through the orifice 65 of the die will be gradually tapered. When it is desired to increase or diminish the amount of taper that is imparted to the wire, by hand, rotation of the hand wheel f^3 causes the worm f' to rotate the worm wheel F , so that the latter, through its key f , rotates the spindle E relatively to the worm wheel E' in which latter the spindle is threaded.

What I claim and desire to secure by Letters Patent of the United States is:—

1. In a machine for tapering wire, the combination of a die, a die socket having a contracting hole, means for automatically forcing the die into such hole during the 80 passage of the wire through the die, and means by which the amount of taper can be increased or diminished while the drawing operation is taking place.

2. In a machine for tapering wire, the 85 combination of a die, a die socket having a contracting hole, a lever for forcing the die into the contracting hole, means for automatically imparting movement to the lever during the passage of the wire through the 90 die, and manually operated means for varying the position of such lever.

3. In a machine for tapering wire, the combination of a die, a die socket having a contracting hole, a lever for forcing the die 95 into the contracting hole, a spindle arranged to exert pressure upon the lever, means for automatically imparting endwise movement to the spindle and manually operated means for varying the position of 100 such spindle.

4. In a machine for tapering wire, the combination of a winding drum and gearing for operating the same, a die, a die socket having a tapering aperture, a lever arranged to exert pressure upon the end of the die, an externally threaded spindle arranged to exert pressure upon the lever, an internally threaded worm wheel mounted upon the threaded spindle, gearing connecting such worm wheel with the gearing that operates the winding drum, a worm wheel mounted upon the spindle and connected therewith by a key and slot connection and a manually operated worm gearing with 115 such worm wheel.

5. In a machine for tapering wire, the combination of a die, a die socket having a contracting hole, means for automatically forcing the die into such hole during the 120 passage of the wire through the die and a wire measuring device for indicating the progress of the tapering operation.

6. In a machine for tapering wire, the combination of a die, a die socket having a 125 contracting hole, means for automatically

forcing the die into such hole during the passage of the wire through the die, means by which the amount of taper can be increased or diminished while the tapering operation is taking place, and a wire measuring device for continuously indicating the progress of the tapering operation.

In testimony whereof I affix my signature in presence of two witnesses.

JAMES ALEXANDER HORTON.
